UNITED STATES PATENT OFFICE.

CHRISTIAN KORTE, OF LEEDS, ENGLAND, ASSIGNOR OF ONE-THIRD TO SAMUEL DENISON AND ONE-THIRD TO GEORGE HENRY DENISON, BOTH OF LEEDS, ENGLAND.

REVOLUTION-COUNTER.

1,077,611.

Specification of Letters Patent.

Patented Nov. 4, 1913.

Application filed August 31, 1911. Serial No. 646,989.

To all whom it may concern:

Be it known that I, CHRISTIAN KORTE, a subject of the King of Great Britain, and resident of Standard Buildings, 38, Park Row, Leads, in the county of York, England, have invented a certain new and useful Improvement in Revolution-Counters, of which the following description, together with the annexed sheets of drawings, is a specification.

My invention relates to apparatus for counting and registering the revolutions of rotary shafts or other revolving bodies and particularly to that type or class of same wherein the timing and counting mechanisms are desired to be put into action simultaneously; and the object of my said invention is the production of devices that may be put into action only by the rotary motion of the shaft or body, the revolutions of which have to be counted and registered and that in such a manner as will insure more effectively the said simultaneous actions, while said devices are of the novel formation, construction and arrangement hereinafter described for effecting said counting and timing functions without relying upon any differences or variations between the movement of one part and those of another part for this purpose. In other words the revolution counter is driven positively while the clock or timing mechanism derives its motion from the positively driven part through or by friction gear and the hands for indicating the number of complete revolutions and the time in which same are carried out are separately carried and actuated by their respective mechanisms and do not rely on any difference or variation that may exist in the movements of the counting mechanism as compared with those of the timing mechanism for effecting their said respective indications.

In the accompanying sheets of drawings which are illustrative of this invention:— Figure 1 is a front elevation or face view of the complete apparatus. Fig. 2 is a front elevation (with the dial removed) of a portion of said apparatus to show certain of the parts hereinafter described. Fig. 3 is a vertical section of the parts shown by Fig. 1 as seen in the direction indicated by the

arrow a. Fig. 4 is a front sectional elevation showing the interior mechanism. Figs. 5 and 6 are front and sectional side elevations showing the formation of a certain part hereinafter described. Fig. 7 is a sectional elevation of a plate wheel used in connection with the parts shown by Figs. 5 and 6. Fig. 8 is a drawing in detail of a key or detachable part hereinafter described.

A indicates the outer casing of the apparatus, B the dial or face indicating the number of revolutions and C the dial or face showing the seconds hand of the clock.

In accordance with my said invention I arrange a pair of worm wheels 2 and 2^a to be actuated by a worm 3 so that each worm wheel 2 and 2^a may rotate its respective ratchet wheel 4 and 4^a arranged in conjunction with it, while said ratchet wheels 4 and 4^a have other wheels 5, 5^a respectively secured to them so that these wheels 5, 5^a may both gear with another spur wheel 6, by which arrangement of mechanism the worm 3 whether rotating in one direction or in the other direction will always transmit motion to the gearing wheel 6 in one and the same direction, said worm wheels 2 and 2^a in conjunction with their ratchet wheels 4 and 4^a which are actuated by the ratchets 7 and 7^a are so arranged as to attain this object since as shown by Fig. 4 if either of the worm wheels moves in such direction as to carry its ratchet 7 or 7^a with it without transmitting motion to its respective ratchet wheel then no motion will be transmitted either to said wheel or to the wheel 6 except through or by the other worm wheel and its ratchet which is rotating in the proper direction to actuate its corresponding ratchet wheel. The worm 3 is mounted or formed upon a spindle 8 the outer end 8^a of which is made to take into a circular or other indentation made in the center of the axis in any shaft whose revolutions have to be indicated so that such shaft will transmit motion to the spindle 8. Or said outer end 8^a may have a sleeve secured upon it to fit or take over the shaft whose revolutions have to be indicated in manner common and well known. On this spindle 8 is secured a flange 9 which takes over anti-friction balls 9^a run-

ning upon a race formed on the casing A as shown by Fig. 3, this flange taking or withstanding any of the pressure or thrust upon said spindle 8 as will be understood.

- 5 The spur wheel 6 is of hollow or box shape as illustrated in detail by Fig. 6, so that within the hollow part of said wheel a spring 10 is mounted to take over a square part of the spindle 11 which is the spindle upon which the large hand 12 is mounted.
- 10 This spring is held by the pin 13 taking through said spindle 11 in order that the resilience of the spring 10 may act upon the wheel 6 and force it against a prepared plate
- 15 14 (of the character hereinafter explained) mounted between it and the box or recessed toothed disk 15 for the purpose hereinafter described. As the spindle 8 revolves it transmits motion to the wheel 6 at a speed
- 20 in unison with it and said wheel 6 by contacting with the spring 10 which is upon the square part of axle 11 transmits its motion to said axle 11 therefore the hand 12 as it rotates over the dial B will indicate the number of revolutions transmitted to and by the
- 25 spindle 8. On the axle 11 is mounted the wheel 31 which gears with the wheel 32 carrying the pinion 33 and this pinion 33 meshes with the wheel 34 so that on the hub of this
- 30 latter may be mounted the hand 35. The wheels 31 to 34 have such relative numbers of teeth that the hand 12 rotates ten times around the dial while the hand 35 moves only the space between two of the indicating
- 35 marks on said dial.
- As means for indicating the time occupied for a given number of revolutions of the wheel 6, this wheel 6 is arranged to transmit motion to timing or clock mechanism
- 40 through the medium of the friction disk 15 as hereinafter described. The teeth on the disk 15 gear with teeth in the wheel 16 upon the spindle of which is mounted the wheel 17 gearing with the pinion 18 secured to the
- 45 spindle of the wheel 19 which wheel 19 through the pinion 20 transmits motion to the pallet wheel 21 which is governed by the usual anchor devices 22 and balance wheel 23, thus by said pallet wheel and its mechanism the rotary motions of the spindle 19^a
- 50 are governed so that according to the adjusting of said governing mechanism each rotation of the spindle will be performed in a given or a known time, hence by placing on
- 55 the spindle 19^a the hand 24 (see Figs. 1 and 3) the time in seconds or otherwise may be indicated by the figures on the dial C. From this it will be seen that the number of revolutions indicated by the hands 12 and 35
- 60 (one indicating tens and the other hundreds of revolutions on the dial B) as having been performed in the time indicated by the clock mechanism as by its hand 24, said number of revolutions per minute (or in any other
- 65 given time as may be found appropriate or

desirable) is clearly shown without necessitating the employment of any other timing mechanism in conjunction with the counting devices.

The frictional devices in order to keep same under constant co-efficient of friction consist as hereinbefore described of the disk 15 and the surface of the wheel 6 between which are interposed any suitable substance as plumbago, which may be rubbed on a piece of cardboard 14, (see Figs. 3 and 6) or the like, or French chalk or like substances may be placed on said cardboard 14 so that the actions of these frictional surfaces as caused through the force of the spring 10 will be kept constant and give the necessary power to drive the clock gearing as above explained, with the result that provided such frictional devices tend to drive the clock gearing too quickly then under the actions of the timing or clock mechanism said frictional devices slip, so that the governing of the whole apparatus as to time is efficiently performed. The central shaft 11 has a square opening made at 11^a to receive the square end of the key 26, see Fig. 8, in order that the user may be able to bring the indicators or hands back to zero after use. The key 26 which is used for this purpose is in its normal position placed in the lower end of the casing as shown by Figs. 1 and 3, where it is held by the spring actuated pin 27 so that its square end may enter the square end of the pinion 28 which meshes with crown teeth 29 formed on the inner surface of the dial C. Thus said key 26 may be employed for bringing the hands 12 and 35 to zero as well as for moving the dial C to bring its zero point opposite the indicating end of the hand 24.

To insure the starting of the clock mechanism immediately the spindle 8 begins to rotate said spindle 8 may be made to have a slight longitudinal movement by leaving its collar 9 clear of the end casing so that a spring may normally force said spindle 8 against such outer end of the casing at which time an extension or coupling from said spindle 8 will move into engagement with the wheel 23 and prevent its further rotation. On the spindle 8 being pressed into contact with the rotary shaft its engagement with the wheel 23 will be disconnected and the spring operating said wheel 23 will immediately start said wheel into motion.

Such being the nature and object of my invention, what I claim is:—

An instrument of the character described having a spindle provided with a free end to be pressed against a rotating member to cause said spindle to be rotated by said member, said spindle having a worm, two worm wheels meshing with said worm, ratchet wheels carried by said worm wheels, spur wheels carried by ratchets engaging with

said ratchet wheels, a hollow toothed wheel, a shaft on which said wheel is mounted, said shaft having an angular portion, a spring fitting said angular portion of the shaft and located in said hollow toothed wheel, revolution indicating hands actuated by said shaft, a friction disk adapted to be driven by the hollow toothed wheel, and a time indicator

and connections for actuating the latter from said friction toothed wheel.

In testimony whereof I have affixed my signature in the presence of two witnesses.

CHRISTIAN KORTE.
